HAROLD S. OSBORNE, OF NEW YORK, N. Y., ASSIGNOR TO AMERICAN TELEPHONE AND TELEGRAPH COMPANY, A CORPORATION OF NEW YORK.

COMPOSITE SIGNALING-CIRCUITS.

1,314,695.

Specification of Letters Patent.

Patented Sept. 2, 1919.

Application filed June 8, 1917. Serial No. 173,528.

To all whom it may concern:

Be it known that I, HAROLD S. OSBORNE, residing at New York, in the county of New York and State of New York, have invented 5 certain Improvements in Composite Signaling-Circuits, of which the following is a specification.

This invention relates to repeater circuits and more particularly to two-way, two repeater circuits associated with composited telephone and signaling lines. Its object is 10 to protect the telephone repeater from signaling currents and to neutralize the effect of such currents upon the repeater.

15 The invention is best understood by reference to the accompanying drawing the figure of which constitutes a circuit diagram of the invention as applied to a two-way two repeater circuit.

20 Referring to the drawing an incoming line L_1 is connected to an outgoing line L_2 by means of a two-way repeater comprising repeater elements R_1 and R_2 . For simplicity these elements are shown as of the mechanical repeater type, but any other type such as, 25 for instance, vacuum tube repeaters, may be used. Repeater element R_1 has its input circuit 1 bridged across the mid-points of windings 2 and 3 of a three winding transformer, 30 the winding 4 of which is in the output circuit 5 of repeater element R_2 . In a similar manner the input circuit 6 of repeater element R_2 is bridged across windings 7 and 8 of a three winding transformer whose 35 third winding 9 is in the output circuit 10 of repeater R_1 .

The left hand terminals of windings 2 and 3 are coupled to the line L_1 through a transformer 11, while the right hand terminals of said windings are similarly coupled 40 through a transformer 12 to an artificial line N_1 designed to balance line L_1 . In a like manner the terminal windings 7 and 8 are coupled through transformers 13 and 14 to line L_2 and artificial line N_2 respectively.

In order that the conductors of the lines L_1 and L_2 may be used for telegraphic or 45 signaling purposes, a connection is made between the conductors of the lines and the artificial lines, and leads extending to Morse or other signaling sets are tapped from these 50 connections. Thus conductor 15 of line L_1 is connected to conductor 17 of artificial line N_1 by a connection including impedance coil 18, contacts 19 and 20 of jack J_1 and plug P_1 ,

contacts 21 and 22 of plug P_2 and jack J_2 and an inductance coil 23. In a like manner conductor 24 of line L_1 is connected to conductor 25 of artificial line N_1 by a connection including inductance coil 26, contacts 27 and 28 of jack J_1 and plug P_1 , contacts 29 and 30 of plug P_2 and jack J_2 and inductance coil 3. Leads 32 and 33 are connected to contacts 21 and 28 respectively and extend to signaling apparatus such as Morse sets. The inductances 18, 23, 26 and 31 are so proportioned as to prevent high frequency telephone currents flowing over line L_1 from being transmitted to the Morse conductors 32 and 33, and also reduce the 70 high frequency components of current which can flow from the telegraph or other signaling line to the telephone line and repeater. At the same time these inductances permit of the passage of low frequency signaling currents such as Morse impulses. 75

In order to prevent Morse impulses from being transmitted to the repeater element R_1 , a wave filter 34 is inserted between the line L_1 and the induction coil 11. Said wave filter is a net-work comprising one or a plurality of sections, each section having a capacity in series with each side of the line, and two serially connected inductances in shunt across the line, the common terminals 80 of each pair of serially connected inductances being connected to ground. The properties of the wave filter are fully described in U. S. patent application Serial No. 40,057 of G. A. Campbell wherein it is 85 shown that a filter consisting of serial capacity and shunt inductance, transmits with negligible attenuation all currents of frequency above a preassigned inferior limit while attenuating and substantially extinguishing all currents of frequency less than said inferior limit. It will be observed that filter 34 consists of two similar halves symmetrically related to ground and for this reason the filter has been termed a duplex 90 filter. The function of the filter 34 is two-fold. First, it prevents low frequency signaling currents from entering the repeater apparatus while at the same time freely transmitting the relatively high frequency 95 telephonic currents. Secondly, by virtue of its duplex structure and ground connections, it prevents the flow of signaling current from one side of the line to the other, and thus largely eliminates interference be- 100 105 110.

tween composited signaling sets associated with the same telephone circuit. A second filter 35 in all respects similar to filter 34 is inserted between artificial line N_1 and induction coil 12 in order to balance the filter in line L_1 .

Should it be desired to disconnect the Morse leads 32 and 33 from the line L_1 , plugs P_1 and P_2 may be withdrawn, thereby permitting the springs 19, 22, 27 and 30 to rest upon their back contacts, thereby associating apparatus 36, 37, 38 and 39 consisting of suitable inductances and capacities with the line to simulate the Morse apparatus so as 15 not to destroy the balance. The telegraphic or signaling apparatus associated with line L_2 and artificial line N_2 is in all respects similar to that above described in connection with line L_1 and artificial line N_1 and hence 20 need not be further described.

The operation is as follows: Telephone currents from line L_1 are transmitted through filter 34 and transformer 11 to the input circuit 1 of repeater R_1 and are amplified by the latter. The amplified currents in output circuit 10 induce currents in the circuit including secondary windings 7 and 8, one-half of the energy in said circuit being transmitted to line L_2 through transformer 13, the other half being transmitted to artificial line N_2 through induction coil 14. Input circuit 6 of repeater R_2 is substantially unaffected by this energy as it is connected to points of equal potential with 35 respect thereto. In a similar manner telephonic currents from line L_2 are repeated by repeater R_2 to line L_1 .

Telegraphic impulses from Morse lead 32 divide at contact 21 part of the current flowing over contacts 20 and 19, through inductance 18 to line conductor 15, and the other part flowing over contacts 21 and 22 and through inductance 23 to conductor 17 leading to the artificial line N_1 .

It has been proposed to reduce the effect of the telegraph or other signaling impulses by the use of series inductances and shunt condensers constituting an upper limiting filter in the telegraph leg to prevent the 45 transmission of appreciable high frequency components of the telegraph current to the telephone line, and to insert between the telephone line and the telephone apparatus series condensers and shunt inductances such as 34 in line L_1 , constituting a lower limiting filter to prevent the low frequency telegraph impulses from being transmitted to the telephone apparatus. By means of this 50 purpose, both in the telegraph branches and in the telephone branch of the circuit, can be reduced because the effect which would be caused in the telephone repeater apparatus is balanced by the neutralizing effect induced through the artificial balancing cir- 60

cuit. This reduction in apparatus reduces the losses in and distortion of energy in both the telephone and telegraph circuits.

Thus, in the figure, inductance coil 18 and other apparatus inserted in conductor 32 70 tends to prevent the high frequency components of the Morse currents from being transmitted to conductor 15 and filter 34 tends to prevent the low frequency signaling currents from being transmitted to the primary of induction coil 11. Such currents as are transmitted to the primary of induction coil 11, however, are balanced by the equal and opposite effect of currents transmitted from conductor 32, through inductance coil 23 to conductor 17 and through filter 35 to the primary of induction coil 12. Therefore, filters 34 and 35, inductance coils 18 and 23 and other apparatus associated with conductor 32 to reduce the magnitude of the 80 high frequency components of the currents can be designed to have a reduced effect on the transmission efficiency of the signaling currents and of the telephone currents. They will then have a decreased effectiveness in preventing the signaling current from reaching the primaries of inductance coils 11 and 12 but the currents reaching those two coils will neutralize each other in their effect on the telephone repeater. 95

Morse currents from conductor 33 are supplied to conductors 24 and 25 in a similar manner and any currents passing from conductor 33 through the filters 34 and 35 induce opposing potentials with respect to the 100 repeater. It will be seen, therefore, that the Morse currents are without effect on the repeater.

If the telephone repeater be operated with the transmitting element bridged across the 105 circuit, that is connected to conductor 1, and the receiving element in the secondary of transformer 4, this same arrangement can be used for balancing the effect of the Morse signals on the telephone repeater, but in 110 this case coil 23 should be connected to conductor 25 and coil 31 to conductor 17.

The artificial line N_1 must be constructed so as to balance with the precision desired the impedance of the metallic telephone circuit L_1 at all frequencies at which it is desired to neutralize the effect of the signaling currents on the telephone repeater by the 115 balancing arrangement here described. In some cases, in order to prevent crossfire between conductors 17 and 25, it may be desirable to construct artificial line N_1 in two equal parts, connected in series with a ground connection at the mid-point between them. 120

While the invention has been illustrated as embodied in a certain specific form, it will be understood that it is capable of wide variation without departing from the spirit of the appended claims. For example, this ar- 125 130

rangement or a similar arrangement can be applied to types of telephone apparatus other than telephone repeaters, such as terminal telephone sets, in cases in which the 5 apparatus is connected symmetrically between the line and a balancing artificial line.

What is claimed is:

1. In combination, a pair of line sections, repeaters for interconnecting said line sections, artificial lines for balancing said line sections, signaling apparatus, a connection between said signaling apparatus and one of said lines, and a balancing connection from said signaling apparatus to the corresponding 15 artificial line.

2. In combination, line sections for telephonic transmission, repeaters for interconnecting said line sections, artificial lines for balancing said line sections, signaling apparatus for a conductor of a line section, parallel branches extending from said signaling apparatus, one of said branches leading to the line conductor, and the other branch 20 leading to a conductor of the corresponding

artificial line so that signaling currents in 25 said branch produce a reaction upon the repeater equal and opposite to that produced by signaling currents in the first branch.

3. In combination, a telephone transmission line, a balancing artificial line therefor, 30 signaling apparatus, a connection from said signaling apparatus to said transmission line, and a balancing connection from said signaling apparatus to said artificial line for balancing said first mentioned connection. 35

4. In combination, a telephone transmission line, a balancing artificial line therefor, signaling apparatus, a connection permitting the flow of signaling currents from said signaling apparatus to said telephone transmission line, a balancing connection to said artificial line, and means to prevent the flow 40 of telephonic current over said connections.

In testimony whereof, I have signed my name to this specification this fourth day of 45 June, 1917.

HAROLD S. OSBORNE.
